UNITED STATES PATENT OFFICE.

NORMAN N. HAZELTON, OF LAMONI, IOWA.

REIN-FASTENER.

SPECIFICATION forming part of Letters Patent No. 297,795, dated April 29, 1884.

Application filed November 24, 1883. (No model.)

To all whom it may concern:

Be it known that I, NORMAN N. HAZELTON, of Lamoni, Decatur county, Iowa, have invented a new and Improved Tug and Rein 5 Fastener, of which the following is a full, clear, and exact description.

My invention consists of an improved hook-and-catch device for connecting harness-straps, particularly tugs and reins, and also 10 adapted for connecting the back-strap and belly-band to the tug, the said hook-and-catch device being contrived for being attached to the straps without stitching or riveting, and more substantially than with buckles, and being 15 adapted to be made very cheaply in malleable iron, all as hereinafter fully described.

Reference is to be had to the accompanying drawings, forming part of this specification, in which similar letters of reference indicate corresponding parts in all the figures.

Figure 1 is a longitudinal section of a rein and my improved hook-and-catch device as applied to the fastening of the rein to the ring of the bridle-bit. Fig. 2 is a side elevation of a tug, back-strap, and belly-band connected with the said fastener; and Fig. 3 is a longitudinal section of Fig. 2.

The catch consists of the back plate, *a*, side flanges, *b*; nib *c*, cross-bar *d*, and one or two 30 loops, *e*, according to whether it is used for the rein-connection or for the tug-fastener. The hook consists of the back plate, *f*, front plate, *g*, hook proper, *h*, loop *i*, and nib *j* for the rein-fastening, and when it is used for the 35 tug-fastening said hook also has the back loop, *k*, and when said hook is also to connect the back-strap and belly-band *l m* it is provided with the front side loops, *n*.

In the use of the said fastener with a driving-rein, *o*, the catch device has two loops, *e*, through which the rein *o* is passed a suitable distance from the end to a hole, *p*, through the strap for securing the catch by the nib *c*. The hook has one loop, *i*, for the rein, through 45 which the rein is passed, and the end is inserted between the front and back plates, *g f*,

and pressed down on and secured by the nib *j*. The hook is then passed through the bit-ring and doubled back and hooked to bar *d*, as represented in Fig. 1.

For the tug-fastening the catch device is made with only one loop, *e*, and is placed on the long part *q* of the tug that is connected to the whiffletree. The hook device has the back loop, *k*, in this case, through which the strap *q* passes, and said strap is also inserted through the leather loop *s*, attached to the back of the short strap *t* of the tug, and the hook *h* is then connected to the bar *d* of the catch device, as represented in Figs. 2 and 3.

When the back and belly band strap *l m* is to be connected to the tug, the hook device has the side loops, *n*, through which said strap is passed, said side loops being located with relation to the nib *j*, that fastens strap *t*, so as to be fastened by said nib. The hook *h* is to be presented to the bar *d* nearly at right angles to plate *a*, as indicated in dotted lines, Fig. 1, to be inserted under said bar. It is then swung around parallel to said plate, and is then effectually secured against unhooking. The draft keeps it in that position, and makes it a safety device incapable of unhooking while in use.

Having thus described my invention, I claim as new and desire to secure by Letters Patent—

1. The combination, with the catch-plate having an end loop, a nib, and side flanges provided with a cross-bar, of the hooked plate having an end loop and a nib, substantially as 80 and for the purpose set forth.

2. In a tug and rein fastener, the combination, with the catch-plate having an end loop, a nib adjacent to said loop, and a cross-bar arranged beyond a longitudinal plane touching the outer end of the nib, of the hooked plate having a nib and a loop at one end, substantially as and for the purpose set forth.

NORMAN N. HAZELTON.
